FIG-4

FIGURE 1 is a front elevational view of the doll in normal position showing my new design.

FIGURE 2 is a side elevational view of the doll in normal position.

FIGURE 3 is a rear elevational view of the doll in normal position.

FIGURE 4 is an enlarged fragmentary perspective view of the doll showing in greater detail the flame configurations of the eyes and the ears, and the contrasting color between the pipe joint body and the head, hands and feet, that characterize my design.

I claim:

The ornamental design for a doll, as shown and described.
